US0D1008750S

(12) **United States Design Patent** (10) **Patent No.:** **US D1,008,750 S**
(45) **Date of Patent:** **** Dec. 26, 2023**

(54) **SEALED JAR WITH HANDLE**

(71) Applicant: **Weigang Chen**, Zibo (CN)

(72) Inventor: **Weigang Chen**, Zibo (CN)

(**) Term: **15 Years**

(21) Appl. No.: **29/814,338**

(22) Filed: **Nov. 5, 2021**

(30) **Foreign Application Priority Data**

Jul. 12, 2021 (CN) 202130439605.1

(51) **LOC (14) Cl.** **09-02**

(52) **U.S. Cl.**

USPC **D7/612; D7/629**
